J. M. SARGEANT

LAMP HEATER

Filed Oct. 9. 1924

UNITED STATES PATENT OFFICE.

JOHN M. SARGEANT, OF ELMIRA, NEW YORK.

LAMP HEATER.

Application filed October 9, 1924. Serial No. 742,679.

To all whom it may concern:

Be it known that I, JOHN M. SARGEANT, a citizen of the United States, residing at Elmira, in the county of Chemung and State of New York, have invented certain new and useful Improvements in Lamp Heaters, of which the following is a specification, reference being had to the accompanying drawings.

- 10 This invention relates to lamp burners, and more particularly to a lamp burner especially adapted for use in conjunction with brooder heaters such as shown in my co-pending applications, Serial Nos. 691, 15 232 and 707,712, filed February 7, 1924 and April 19, 1924, respectively, of which later application this application is a continuation in part.

An important object of the invention is to 20 provide in a round wick burner a flame spreader steadyng the flame from the wick and spreading the same so that a flame similar to that produced by a flat wick is provided and smoke from this flame, when the wick is turned up, is eliminated unless, of course, it is turned up to an unreasonable extent.

A still further object of the invention is to 30 provide a lamp burner, the parts of which are readily assembled and disassembled, thus permitting the burner to be frequently cleansed, as is necessary when the burner is employed in conjunction with a brooder, incubator or the like.

35 These and other objects I attain by the construction shown in the accompanying drawings, wherein for the purpose of illustration is shown a preferred embodiment of my invention, and wherein:—

40 Figure 1 is a perspective of the lower end of the chimney of a lamp burner constructed in accordance with my invention;

Figure 2 is a perspective of the flame spreader;

45 Figure 3 is a perspective of the burner dome;

Figure 4 is a perspective of the burner dome support;

50 Figure 5 is a vertical sectional view through the assemblage;

Figure 6 is a vertical sectional view to that shown in Figure 5 and taken through

the burner dome and upper end of the wick tube and flame spreader.

Referring now more particularly to the drawings, the numeral 10 indicates a burner neck threaded at its lower end, as at 11, for engagement in the filling opening of the fuel reservoir and having extending upwardly therefrom centrally thereof a circular wick tube 12. This neck is provided with the usual adjusting element 13, by means of which the wick 14 contained within the tube may be raised and lowered. This means being old and well known, it is not herein illustrated other than by showing the operating shaft thereof.

Extending upwardly from the sides of the burner neck and secured thereto is a circular burner dome support 15 having straight side walls provided with circumferentially spaced openings 16, by means of which air may be admitted to the interior of the support about the wick tube 12 which the support surrounds. The upper edge of this wall is provided with circumferentially spaced, segmental, horizontally and outwardly directed flanges 17, the purpose of which will presently appear.

The burner dome proper 18 is of the usual construction, with the exception of the fact that the slot 19 thereof is widened at its lower end and extends downwardly into the side walls of the dome, this widening of the slot being indicated at 20. The lower walls of the widened portions of the slot are provided in alignment with the slot 19 with V-shaped notches 21, the purpose of which will hereinafter appear.

From the lower edge of the burner dome extends a horizontal flange 22 provided with circumferentially spaced openings 23 to permit the passage of air. The edge of this flange is provided with a plurality of downward extensions 24 corresponding in number and arrangement to the flanges 17 of the burner dome support 15. The lower ends of the extensions are provided with inwardly directed portions 25 having their inner edges arranged upon a circumference equal to the outer diameter of the burner dome support and the extensions themselves being of a width slightly less than the distance between adjacent edges of the flanges 17.

By applying the burner dome to the upper surface of the support so that these extensions engage between the flanges 17 and then giving the same a partial rotation, the inwardly directed portions 25 underlie the flanges 17, upon the upper surface of which the flange 22 is at rest, thus preventing displacement of the burner dome. Between the downward extensions 24 the edges of the flange 22 are provided with upward extensions 26, the upper edges of which are formed with inwardly extending portions 27 adapted to receive segmental flanges 28 formed upon the lower end of a chimney 30 and corresponding in structure to the flanges 17 of the burner dome support 15. Thus the burner dome provides means not only for attaching the burner dome to the burner dome support but also means for attaching the chimney to the burner dome.

Mounted upon the upper end of the wick tube is a short sleeve 32 having extending outwardly and upwardly therefrom at opposite sides thereof a pair of wings 33 which rest in the lower ends of the slot. These wings, in addition to inclining upwardly and outwardly, are V-shaped in cross section. Extending outwardly at right angles to the wings 33 are a pair of flanges 34 which extend into proximity with the walls of the dome and direct air passing upwardly through the dome against the inner wall of the dome by which it is directed in leaving the overhanging lips 35 of the dome substantially horizontally against the flame arising from the wick 20. The structure 32, 33, 34 combines a flame spreader in combination with a circular wick and will form a flat narrow band of flame such as is ordinarily provided by a flat wick.

It will be obvious that a burner of this character may be very cheaply and readily produced and is readily disassembled for cleansing, thus rendering less likely neglect of the burner, which often results in fire or smoking burners which have disastrous effects on the contents of the brooder or incubator.

It will be obvious that the device as above described is capable of a considerable range of change and modification without materially departing from the spirit of my invention and I accordingly do not limit myself to such specific structure except as herein-after claimed.

I claim:—

1. In combination with a burner dome having a slot in its upper end and extending transversely thereof, the upper wall of the dome forming at the sides of the slot inwardly directed baffle walls, a tubular wick holder projecting axially into the lower end of the burner dome, and a flame spreader removably engaged with the upper end of the wick holder, comprising a sleeve en-

gaging the wick holder having diametrically opposed, upwardly and outwardly inclining wings V-shaped in cross section, said sleeve being provided at right angles to said wings with outwardly extending horizontal flanges directed toward the adjacent walls of the dome and directing air against such walls in passage upwardly thereagainst whereby said air engages against the flame above the horizontal baffles of the burner dome to spread the flame from a wick contained within said wick tube. 70

2. The combination with a burner dome having a slot in its upper end extending transversely thereof, the upper wall of the dome forming at the sides of the slot inwardly directed baffle walls constricting the slot at its upper end, the lower walls of the slot having V-shaped notches therein, a tubular wick holder projecting axially into the lower end of the burner dome, and a flame spreader removably engaged with the upper end of the wick holder comprising a sleeve engaging the wick holder having diametrically opposed, upwardly and outwardly inclining wings V-shaped in cross section, the ends of said wings extending into and having their lower surfaces fitting against the walls of the notches at the lower ends of the slot. 80

3. In a wick burner construction, a burner neck having an axially disposed wick tube, a burner dome support extending upwardly from said burner neck in spaced relation to the wick support and surrounding the same and provided in its side walls with perforations, said dome support being provided upon its upper outer edge with spaced, outwardly extending flanges, a burner dome adapted to seat upon the upper surface of the burner dome support and having upon its periphery alternate upwardly and downwardly extending flanges, each provided with a portion paralleling the burner dome in vertically spaced relation thereto, said downwardly extending flanges together with the portions thereof paralleling the burner dome receiving the flanges of said burner dome support to secure the burner dome in position thereon, and a chimney having at its lower end outturned flanges corresponding in number and arrangement to the upturned flanges of the burner dome and adapted to coact therewith to maintain the chimney in position upon the burner dome. 90

4. In a wick burner construction, a burner neck having an axially disposed wick tube, a burner dome support extending upwardly from said burner neck in spaced relation to the wick support and surrounding the same and provided in its side walls with perforations, said dome support being provided upon its upper outer edge with spaced, outwardly extending flanges, a burner dome adapted to seat upon the upper surface of the burner dome support and having upon its periphery alternate upwardly and downwardly extending flanges, each provided with a portion paralleling the burner dome in vertically spaced relation thereto, said downwardly extending flanges together with the portions thereof paralleling the burner dome receiving the flanges of said burner dome support to secure the burner dome in position thereon, and a chimney having at its lower end outturned flanges corresponding in number and arrangement to the upturned flanges of the burner dome and adapted to coact therewith to maintain the chimney in position upon the burner dome. 100

the burner dome support and having upon its periphery downwardly extending flanges, each provided with a portion paralleling the burner dome in vertically spaced relation thereto, said downwardly extending flanges together with the portions thereof paralleling the burner dome receiving the flanges of

the burner dome support to secure the burner dome in position thereon and means for supporting a chimney from the burner dome. 10

In testimony whereof I hereunto affix my signature.

JOHN M. SARGEANT.
